UNITED STATES PATENT OFFICE.

ANDREW THOMA, OF CAMBRIDGE, MASSACHUSETTS, ASSIGNOR TO NORTH AMERICAN CHEMICAL COMPANY, OF NEW YORK, N. Y., A CORPORATION OF MAINE.

METHOD OF USING SHOE-BOTTOM FILLER

1,118,161.

Specification of Letters Patent. Patented Nov. 24, 1914.

No Drawing. Original application filed March 7, 1907, Serial No. 361,171. Divided and this application filed April 8, 1912. Serial No. 689,395.

To all whom it may concern:

Be it known that I, ANDREW THOMA, a citizen of the United States, and resident of Cambridge, in the county of Middlesex and State of Massachusetts, have invented an Improvement in Methods of Using Shoe-Bottom Filler, of which the following description is a specification.

This case is a division of my application Serial No. 361,171, filed March 7, 1907, and relates to the method or process of using shoe-bottom filler by introducing into the filler, or using in direct connection with the filler itself, moisture, preferably steam. Heretofore, in the use of shoe-bottom filler (of the kind, for instance, set forth in my Patent No. 832,002 of September 25, 1906), it has been customary to provide a kettle, preferably steam-jacketed, such as is shown in Patent No. 808,227 of December 26, 1905, in which the loaf of filler is placed and heated with a dry heat until it is softened or loosened by the melting of its binder and thereby rendered sufficiently plastic to be laid in the shoe-bottom cavity, whereupon a small quantity is deposited in the cavity and unified and laid by a spatula or knife which the workman slides and presses over the loosened and plastic mass of filler by a motion somewhat as a mason levels mortar with a trowel, and the filler is then instantly subjected to a superheating and vertical pressure (as in said Patent No. 808,227). The art is set forth in my Patent No. 808,224, of December 26, 1905. One of the great difficulties and objections to this method of use of the filler is that the careless operator, not realizing the sensitive character of the low-heat responsive filler, is very liable to leave the steam turned on so long or at such a temperature as to destroy the intrinsic quality of the filler, particularly of the vegetable gums or other sticky binder contained therein, and sometimes even char the cork so that the tough cohesion of the filler is practically destroyed. Notwithstanding the provision of special means for regulating the heat, I soon found that the careless operator would nevertheless burn or injure the filler by overheating.

Accordingly, the present invention aims to obviate this trouble by introducing moisture into the filler itself at the time of using

the same, thereby rendering the filler less amenable to destructive heat, besides introducing various important and practical advantages, as will appear more at length in the course of the following description. In connection with this process, I have discovered also that by means of the moisture, and particularly when in the form of moist heat, various latent qualities and properties of the filler may be developed at the time when they are required for use. This subject is quite fully developed in my copending application Serial No. 686,977 and in Serial No. 432,083 (now Patent No. 1,082,312), which also consider a filler differing from that first mentioned above in many particulars, chief of which is in containing ingredients constituting, or capable of forming, a volatile solution, such, for instance, as aqueous paste, for ultimately stiffening or setting the remaining meltable ingredients of the filler. My present parent case Serial No. 361,171, while not contemplating such paste stiffening components, employs the meltable gummy constituents, together with fluxing agents and conditions whereby the gums are completely disintegrated and preferably mixed into the filler by a friction milling process.

Referring now to the particular kind of filler disclosed and claimed in the said parent case of which this is a division, this process has a particular advantage of developing in the vegetable gums of said filler (or for that matter in the gums of my foundation Patent No. 832,002 above referred to) a better stickiness. Also it develops a far more sensitive, better stickiness in the entire filler mass than would be the case if dry heat alone were used. In my said parent application, I provide a filler in which the gums (pontianac and gutta percha, for example) are turned into a highly sticky condition without having their stringy tenacious nature wholly eliminated by heat (as was apt to be the case in the method set forth in Serial No. 432,083, above). This is especially the case where the aforesaid milling process is used in addition to heat, in which case the full strength of the gums has been left uninjured, requiring force to spread it throughout the mass of granulated material. One of the advantages resulting from this kind of a filler is that the filler

loaf or cake (*i. e.* supposing that the product is put up in that shape as set forth in my before mentioned Patent No. 832,002) can be readily reduced to the proper consistency for direct application (by hand, it may be) to the shoe-bottom cavities by simply being placed in the steam bath, such, for instance, as may be provided by an apparatus similar to a glue pot, but having the inner pot shallow and perforated so as to permit the steam and moist vapor to percolate and penetrate through the filler mass, helping quickly to soften and disintegrate the same, and thereby place it in condition to be handled and to be quickly molded into the bottom cavities of the shoes. The hot moisture, although unable to disturb the binding agent of the mass, helps to soften the same by interposing the moisture layer or film between the different particles so as to make them cling together less tenaciously and thereby separate the material into a workable condition so that it may be handled quickly and easily, *i. e.*, without any strong resistance to the laying tool (the spatula first referred to above) or lifting tool which it would otherwise have. The moisture also puts the filler into such a condition that it is not so liable to stick to the heated tools when being laid in the shoe and gives it a non-resisting, readily moldable and workable character, while yet remaining quick-setting, permanently tenacious, elastic, and unchangeable in the sense set forth in my before mentioned shoe-filler Patent No. 832,002.

It will be understood that my present method or process is not restricted to any one of the kinds of filler mentioned, but is intended to apply to the general character of filler as broadly defined in my Patent No. 832,002 and contained in subsequent patents and copending applications.

Another machine for carrying out this method or process is disclosed in my application Serial No. 686,977, filed March 28, 1912, and I intend certain of the claims of the present case to be generic to the process disclosed in the last mentioned application.

Having described my invention, what I claim as new and desire to secure by Letters Patent is:

1. The herein described method, consisting of providing a shoe bottom filler containing filler-body material mixed with a binding agent which contains a vegetable gum and which is permanently cementitious, elastic, waterproof and adhesive, and is influenced by moisture and by heat, subjecting said filler to moisture and to heat until softened, and applying the same to the shoe-bottom while thus soft, substantially as described.

2. The herein described method, consisting of providing a quick-setting tenacious

communited shoe-bottom filler normally having a certain degree of stickiness which is latent and capable of being developed by subjection to moisture in the form of steam, heating the filler and simultaneously permeating the same throughout all the interstices thereof with an even flow of said moisture until the latent stickiness is fully developed, and then immediately applying the filler to a shoe-bottom cavity while in said condition, whereby the superficial moisture minimizes the tendency of the sticky filler to adhere to the applying tool and the interstitial moisture further relieves the tendency to fatigue the operator by giving the filler a temporary non-resisting character without destroying the quick-setting tenacious character of the laid filler when the steam has evaporated, substantially as described.

3. The herein described method, consisting of heating a shoe filler of the character herein set forth, which is influenced by moisture and by heat, in a moist bath of steam until softened and partially disintegrated, and then quickly molding the filler into a shoe-bottom while still soft, substantially as described.

4. The herein described method, consisting of providing a filler containing comminuted material and a binder which is, at least in part, meltable, said filler being influenced by moisture, melting the filler and permeating the same throughout all the interstices of said comminuted material with moisture sufficient in amount to bring the same to a workable state, and then immediately applying the filler to a shoe-bottom cavity substantially as described.

5. The herein described method, consisting of providing a filler containing comminuted material and a binder which is influenced by moisture and by heat, permeating the same throughout all the interstices of said comminuted material with hot moisture sufficient in amount to bring the same to a workable state, and then immediately applying the filler to a shoe-bottom cavity substantially as described.

6. The herein described method, consisting of providing a filler normally having a certain degree of stickiness which is latent and capable of being developed by subjection to moisture in the form of steam, heating the filler and simultaneously permeating the same with an even flow of said moisture until the latent stickiness is fully developed, and then immediately applying the filler to a shoe-bottom cavity while in said condition substantially as described.

7. The herein described method, consisting of providing a filler of comminuted material mixed with a binder which is influenced by moisture and containing a gummy constituent which is responsive to

heat, heating the filler in the presence of moisture until the filler is loosened to a readily layable condition, and then laying the loosened filler in a shoe-bottom cavity substantially as described.

8. The herein described method, consisting of providing a filler of comminuted material mixed with a binder which is influenced by moisture and containing a water-insoluble component capable of developing stickiness for holding the filler in place in the shoe-bottom cavity, heating the filler in the presence of moisture until said stickiness

is properly developed and the filler is brought to an easily manipulated loosened condition, and then laying the loosened filler under pressure in the shoe-bottom cavity substantially as described.

In testimony whereof, I have signed my name to this specification, in the presence of two subscribing witnesses.

ANDREW THOMA.
